UNITED STATES PATENT OFFICE.

ISAAC B. DAVIS, OF HARTFORD, CONNECTICUT.

DESIGN FOR STEAM-PUMPS.

Specification forming part of Design No. **11,252**, dated June 17, 1879; application filed April 26, 1879.
[Term of patent 7 years.]

To all whom it may concern:

Be it known that I, ISAAC B. DAVIS, of Hartford, in the county of Hartford and State of Connecticut, have invented a Design for Feed-Pumps, of which the following is a specification.

My design is clearly represented in the accompanying photograph, in which—

A represents a base-plate, the central portion of which is extended upward and fashioned into two upright cylinders, *a*, arranged side by side. From opposite sides of the cylinders two valve-cases, of a general rectangular form, are extended, as shown at B and C. From the outer sides of the respective cylinders *a* two arms or standards, D, are extended upward, and rounded and fashioned into two bosses or bearings, *d*. Transverse shafts E F will be seen extending through the bosses or bearings from one upright to the other. On the upper shaft may be seen a gear-wheel, G, and two eccentrics, H. Two pitmen, I, will

be noticed extending downward from the eccentrics and vanishing in round plungers J, the upper ends of which are exposed above the cylinders. On the lower shaft, F, there will be seen a central pinion, K, and two outside smooth pulleys, L.

The precise form of the various parts, their relative arrangement, and the appearance which the design presents to the eye can be readily and fully understood only by reference to the photograph.

Having described my design, what I claim is—

The design for a feed-pump, embracing the base, upright cylinders, projections B C, standards D; and the cross-shafts and gearing, as shown.

ISAAC B. DAVIS.
